GEORGE CAHILL, OF NEW YORK, N. Y., ASSIGNOR TO ISAAC G. JOHNSON,
J. F. HUNTER, AND PETER P. KELLER, OF SAME PLACE.

Letters Patent No. 77,453, dated May 5, 1868.

IMPROVED MACHINE FOR TAPPING AND DRILLING.

The Schedule referred to in these Letters Patent and making part of the same.

TO ALL WHOM IT MAY CONCERN:

Be it known that I, GEORGE CAHILL, of the city, county, and State of New York, have invented a new and improved Tapping and Drilling-Machine; and I do hereby declare that the following is a full, clear, and exact description thereof, which will enable others skilled in the art to make and use the same, reference being had to the accompanying drawings, forming part of this specification, in which—

Figure 1 represents a side elevation of my improved tapping and drilling-machine.

Figure 2 is a detail elevation of the opposite side.

Figure 3 is a detail horizontal section of the same, taken on the plane of the line x x , fig. 1.

Figure 4 is a detail horizontal section of the same taken on the plane of the line y y , fig. 2.

Similar letters of reference indicate corresponding parts.

The object of this invention is to facilitate the setting of the turn-over tap-stock of a machine for tapping or drilling pipe-fittings without requiring the shaft on which the device turns to be stopped for such setting of the tap-stock.

In the machine herein referred to, a tap-stock or chuck, having two or more arms of different diameters, is hung by a pivot in the forked end of a rotating spindle. When a pipe or elbow of different diameter from that previously worked on is to be tapped, the stock must be turned so as to bring the desired arm into line with the axis of the spindle. To turn the stock for this purpose is the object of my invention.

Heretofore such adjustment could only be performed by stopping the motion of the spindle, or by, with danger to life and limb of the operator, drawing out by hand the pin that locks the stock, turning by hand the stock to the required position, and replacing the pin, all while the spindle is in motion. If the spindle is stopped, the operation of the machine is seriously delayed. If the stock is released, set, and relocked, by hand, during the revolution of the spindle, the operation is also frequently delayed, and is certainly made uncertain and dangerous.

An improvement which would obviate the aforesaid drawbacks, and which would permit the shifting of taps without delay or annoyance, is, therefore, a great desideratum, and is fully obtained by my invention.

My invention consists in connecting with the fork of the spindle a lever, which, when raised or depressed, withdraws the stop-pin, and then turns the stock in the desired direction, and allows the stop-pin to resume its original position, and to lock the stock, until another change is required.

The lever does not turn on or with the spindle, and is always within easy reach, so that the stock can be set with ease and facility without interrupting the motion of the spindle.

Upon the solid part or top of the fork A of the spindle B is fitted an up-and-down sliding collar, C, which turns with the spindle, and rises or falls with it, but which also slides up and down upon it within the space provided for it between two shoulders, a and b , on the spindle, so that it has a suitable desired play. Around the collar C is a friction-band, e , having two pins d d at opposite points, which pins serve as pivots and supports to a forked lever, D, as shown. The forks of the lever D project beyond the spindle, as shown in fig. 4, and are furnished with upright curved fingers e e , that take hold loosely of the edge of the circular shoulder or disk a , which is secured to the top of the spindle-fork, and which, consequently, serves the double purpose of a stop, to keep the collar C in place, and of a fulcrum for the lever D, when it is operated.

The ends of the forks of the lever D are pivoted to a forked jointed bar, E, which is hinged to the under side of a stationary bracket, f , of which can be attached to the face of the upright, F, that supports the brackets, and which jointed bar serves to keep the lever D from turning with the spindle.

When the construction of the "fork" does not admit of the use of the collar C, band e , lever D, and arm E, the lever can be directly pivoted to the fork; and can then be used without any material difference in

effect, as the principle of operating by means of a lever remains the same; the only difference being, that, in one case, the lever stands still, and in the other it revolves with the spindle.

To operate the "stop" pin, there is placed on one face of the fork a jointed lever, G, which is properly connected with the collar C, when that is used, or, if the lever D is directly pivoted to the fork, with the lever. The lower end of the lever G is pivoted to a swinging cam, H, which is pivoted to one face of the fork A, and which has a cam-flange, g, as in fig. 1.

I is the stop-pin, fitting through the fork into the stock J. The pin I has an upward-projecting pin, h, with a V-shaped inner face, as in fig. 3, which pin h is, by a coiled spring, forced against the face of the fork. When the lever D is raised, as shown by red lines in fig. 1, the cam H is brought between the lug h and the fork A, and draws the pin I out of the stock.

On the other face of the fork are two levers, K K, pivoted to the fork, and carrying each a projecting pin, j, that is fitted through a slotted strap, L, which is connected with the collar C, when it is used, or with the lever D, if the same is directly pivoted to the fork A, and which acts, when raised or lowered by means of the lever D, upon the pins j, and thereby oscillates the levers K. Through the lower slotted end of the strap L is fitted a thumb-screw, k, which serves to keep the lower end of the strap in place. The pins j fit through slots in the strap, which are either square, round, or elliptic, and which are designed to be somewhat larger than the pins upon which they act, for a reason to be hereinafter shown.

From the arms K K project ears l l, into which are swivelled respectively vertical rods M M, each of which is provided at its upper end with adjusting-nuts, as shown, for suitably adjusting the rods, and permitting them to play easily in the swivels, as the arms K K rise and fall.

To the lower ends of the rods M M are respectively attached two arms N N, which turn loose on the pin O that carries the stock J, and which arms N act on the toothed edge of a disk, P, that is mounted on the pin or axle O.

Outside of the arms N N is arranged, around the pin O, a rubber disk, between two plates of thin metal, which rubber disk constitutes a spring for the purpose of keeping the arms N N tightly pressed against the face of the disk P.

When it is required to use only two taps, a shoe, m, is placed under one of the arms N, and a thumb-screw, w, is placed in one of four, more or less, holes of the disk P, as shown in fig. 2. By these means, the disk and shaft O are acted upon by one arm, N, only, the other being raised by the shoe above the projecting cam-points of the disk, and is thus inactive, though free to move up or down.

This device of the shoe and thumb-screw produces an alternate or oscillating movement, and enables the workman to use two taps, when necessary, without loss of time; one pressure of the hand on the lever D causing the turn-over or stock to swing in one direction, and the next pressure causing it to move back again. When the shoe and thumb-screw are not required, they are removed.

Without the shoe and thumb-screw, the motion of the crown-shaft O, and consequently of the stock, turn-over, or tap-stock J, is in one direction only, whether the lever D is moved up or down. Thus, when the lever is pressed down, one of the arms N pushes the crown P on the shaft O by means of one of its points or teeth, while the other arm N passes over a point or tooth. When the lever is raised, the disk is pulled a quarter turn by the other arm N, while the arm which acted with the downward motion now passes over the points or teeth of the disk P. These cam-shaped teeth are four, or more or less, in number, and are all pointed in one direction, so that force can only be applied to produce a movement in one direction, though itself applied in two opposite directions, upward and downward. It is thought that no means so simple and easily constructed as these can be applied and used as effectually to accomplish the same results.

The action of the different parts is further explained thus:

The lever D, when moved up or down by the hand of the workman, imparts motion to the arm or lever G, and to the slotted strap L, which motion is designed, in a full-sized machine, to extend through the space of half an inch, more or less.

During the first part of this motion the cam H swings and passes beneath the head h of the stop-pin I, and lifts it out of its hole in the turn-over, and leaves the latter free to move. Then the strap L begins to act on the pins in the arms K K, having, while the cam H was turned, moved without affecting the arms K, because of the enlarged slots through which the pins j pass, and upon which the strap acts. The strap L and cam H now move together through the next part of the motion; the strap L, by means of its connections, acting on the shaft O of the turn-over or tap-stock, and the cam h sustaining the stop-pin until near the end of the move, when it is withdrawn from beneath the head of the pin, and thus permits the pin at the proper time to drop into the proper recess or hole in the turn-over, and to thus secure the same in its new position. The cam H is shown by red lines in fig. 1 to be near the end of its stroke.

Thus, by the aforesaid means, which are simple enough in themselves, "one pressure" of a lever, either upward or downward, enables the workman to change his taps quickly and safely, without delay, danger, or annoyance, at the quickest speed of the machine at which he may be working.

Having thus described my invention, what I claim as new, and desire to secure by Letters Patent, is—

1. The combination of the collar C, friction-band e, forked lever D, fingers e e, shoulder a, jointed arm E, or their respective equivalents, all constructed and arranged in the manner and for the purpose specified and set forth.

2. I claim the system of levers G, cam H, and pin I, when constructed, combined, and applied to the forked spindle of a tapping-machine, in the manner and for the purpose herein specified and set forth.

3. I claim the forked lever D, movable collar C, slotted strap L, the lever-arms K K, rods M M, arms N N, shaft O, disk P, all constructed and combined, and all applied to and used upon the forked spindle of a tapping machine, in the manner and for the purpose specified and set forth.

4. I claim the improved tapping-machine, consisting of the several parts hereinbefore specified, all constructed and arranged substantially as described.
